NONWARPING STOVE TOP

Filed Oct. 26, 1925

Patented June 14, 1927.

1,632,060

UNITED STATES PATENT OFFICE.

GEORGE DOUGLAS, OF SAN FRANCISCO, CALIFORNIA.

NONWARPING STOVE TOP.

Application filed October 26, 1925. Serial No. 65,034.

This invention relates to a top for ranges of all kinds, and its object is to provide a top that will not be subject to warping because of the heating from the burner.

5 Another object of the invention is to provide a smooth top, one of the members of which will fit upon and overlock the next adjacent member, each member, therefore tending to support the other, and aid in preventing either from warping to the extent that commonly takes place with such ranges.

Another object of the invention is to provide a top for stoves of the so called French range, or removable top type, whether burning 15 gas, oil or coal, one member of which will be used as a warming plate, while the other members are used for cooking, the arrangement being such that there are two or more cooking plates, and then one warming plate 20 aiding in supporting the one edge of each cooking plate, where only two cooking plates are used.

An embodiment of the invention is shown in the accompanying drawings in which the 25 same reference numeral is applied to the same portion throughout, but I am aware that there are modifications thereof:

Fig. 1 shows a plan view of the top of such a stove as is herein contemplated, consisting 30 of two warming plates and two cooking plates;

Fig. 2 is a sectional view of a portion of the top of the stove shown in Figure 1;

Fig. 3 is a sectional view through the 35 burner plate on the line 3—3;

Fig. 4 is a sectional view of the second cooking plate on line 4—4.

In the first instance, a portion of the stove is shown with the top plates 1 to 4 inclusive, 40 and a portion of a plate 5, which is substantially identical with the plate 2. Each of the plates is provided with an exterior groove as indicated at 6, said grooves aligning with one another to prevent grease 45 spilled on the stove top from running off the edge of the stove.

It will be seen that there are four kinds of plates; the plate 1 is an end plate. The plate 2 is the plate for the burner, and it is 50 provided with a removable member 7 in order that the fire may be examined, or more heat obtained, whenever necessary. Plate 3 is a secondary cooking plate, while the plate 4 is a dead end plate the same as the end 1,

except that it is provided with the over-lap 55 ledges 11 and 12 on its opposite edges, while the plate 5 is the same as the plate 2.

It will be seen that the plates 1, 2 and 3 have over-lapping edges as indicated at 9—10, and each of the plates 2 and 3 is provided with a series of hollow ribs as indicated at 8, 13, 14, 15, 16 and 17, while the plate 2 has the transverse ribs 18, 19, 20 and 21, the plate 3 having one transverse rib 22. All of these ribs are hollow, and so are each provided with an asbestos insulation to aid in preventing the ribs from warping.

In order to provide the members 2 and 3 with sufficient insulation surface to prevent warping, it will be seen from the construction described above, that each of the plates 2 and 3 is provided with crossing portions which will be kept more or less cool by the body of the asbestos insulation, and that these cool portions will tend to hold the two 75 plates perfectly straight.

The position of the burners, whether oil or gas, with respect to the several plates, is indicated in Figure 2, the plate 2 already 80 serving as a cover for the fire box.

Having thus described my invention, what I desire to secure by Letters Patent of the United States, is as follows, but modifications may be made in carrying out the invention shown in the drawings and in the above 85 particularly described form thereof, within the purview of the annexed claims:

1. A cast iron cover for ranges, comprising smooth top sections having overlapping edges whereby a cover of any desired length 90 may be built up, transverse and longitudinal hollow ribs cast on the bottom portion of said top, said hollow ribs being filled with asbestos.

2. A non-warping range top, comprising 95 thick flat top plate sections having overlapping side edges, spaced longitudinal hollow ribs intersected by spaced transverse hollow ribs, said hollow ribs being filled with fire proof insulation.

3. A top for ranges and the like comprising a plate provided with an open ended heat insulating bore extending therethrough in a plane parallel with the top surface.

In testimony whereof I have hereunto set 105 my hand this 2nd day of October A. D. 1925.

GEORGE DOUGLAS.
